JAMES WESTHALL BROWN, OF BROOKLYN, NEW YORK.

RE-FORMING OF FILMS OF ELECTROLYTIC LIGHTNING-ARRESTERS.

1,104,620.

Specification of Letters Patent.

Patented July 21, 1914.

Application filed January 7, 1914. Serial No. 810,895.

To all whom it may concern:

Be it known that I, JAMES WESTHALL BROWN, of Brooklyn, New York, United States of America, have invented certain new and useful Improvements in the Re-Forming of Films of Electrolytic Lightning-Arresters; and I do hereby declare that the following is a full, clear, and exact description of the same.

10 My invention relates to electrolytic lightning arresters adapted to protect a transmission line from the effect of lightning, static charges, abnormal frequencies or potential due to surge effects or resonance and the like. 15 The electrolytic lightning arrester to which my invention appertains is connected in series with a spark gap inserted between the arrester and the transmission line to be protected and is of the type wherein trays of 20 aluminum are immersed in a suitable electrolyte and upon which films of hydroxid are formed when an electric current is passed through the arrester. The spark gap is adjusted to prevent the jumping of the current 25 of the transmission line at normal voltage and a sufficient number of trays are provided to form films setting up a resistance to hold back such normal voltage. When this voltage is exceeded as will occur when a lightning discharge takes place over the transmission line, the current jumps the spark gap and breaks down the films in the arrester and passes through the latter until the voltage falls below the critical point and at 30 this time the films reform and resist further flow of current through the arrester. No current passes through the arrester under normal working conditions and consequently the films deteriorate and it becomes necessary to periodically build up the films by 35 passing an electric current through the arrester and my invention relates particularly to this charging of the arrester.

As the films of the arresters of the designed type are so proportioned as to break down at a voltage somewhat higher than the normal voltage of the line to be protected, it has heretofore been considered necessary to apply the full or part potential of the line 40 to the arrester in order to send enough current through it to build up the films and this has been done by bridging the spark gap at intervals. The initial flow of the full voltage of the transmission line through the arrester results in dangerous surges and rises 45 of potential in the line which break down in-

sulations to such an extent that the usefulness of the arresters is practically offset by the damage resulting from the charging of the same.

The object of the present invention is to provide means for establishing the films of hydroxid on the aluminum trays of electrolytic lightning arresters without causing surges and disturbances in the transmission line.

The desired object is achieved by isolating the arrester from the transmission line and reforming the films in the arrester by means of an electric circuit separate from or additional to that of the line to be protected. For full comprehension, however, of my invention reference must be had to the accompanying drawings forming a part of this specification in which similar reference characters indicate the same parts and wherein:

Figure 1 illustrates, diagrammatically, an electrolytic lightning arrester of the described type, isolated from the transmission line and connected to the circuit, independent of the latter, in readiness to have the films built up; Fig. 2 shows a modification of the arrangement in Fig. 1; Fig. 3 is a vertical section of an arrester constructed according to my invention; and Fig. 4 is a plan view with the cover removed.

In Fig. 1 the usual arrangement is shown, inasmuch as a horn gap 2 is inserted between the conductor 3 and the electrolytic lightning arrester 4. Heretofore the arrester was charged by bridging the gap 2 and thus passing the full voltage of the main line current through the arrester but, as has been pointed out, this results in surges and other dangerous disturbances on the main line and to avoid these disturbances in the charging of the arrester I first isolate the same from the main line conductor 3 by swinging one of the horns of the gap clear of the other, as shown in Fig. 1, and then charge the arrester by any suitable available electrical circuit such as that indicated at 5 and which is separate from or independent of that of the main line 3 and of less voltage.

As the hydroxid film of each tray resists electric current up to a certain voltage and therefore requires the passage of a similar voltage to build it up I consequently have the trays of the arrester tapped off into groups which each contain trays of a number suitable to the voltage of the charging circuit 5. These groups are then connected

in parallel and a switch 6 closed to connect the charging circuit with the arrester. When the hydroxid films are completely broken down an abnormal rush of current 5 takes place through the arrester when the switch 6 is closed and before the film commences to reform and to avoid this I insert a rheostat resistance 7 in series to the circuit 5 and am thus enabled to set up a resistance to 10 overcome the initial abnormal rush of current and then gradually reduce such resistance as the films are formed and the resistance in the arrester thereby increased. If desired the same advantageous results may 15 be secured by stepping the current down from the main line by means of a transformer 8 (see Fig. 2) and utilizing the transformer as the source of the charging current.

20 In Fig. 3 I have shown one arrangement whereby the groups of trays are arranged in parallel. In this view the aluminum trays are indicated at 9 and as usual are located in a tank 10 which is 25 filled with oil for insulation purposes. The trays are tapped off into groups of equal number by suitable connections such as the terminals 11 which are connected to the trays in such manner that the terminals of 30 alternate groups are at opposite sides of the trays. The terminals are so designed that they will in no way interfere with the ordinary working of the arrester and are supported by strips 11^a of treated wood or 35 other insulating material preferably supported as shown by arms 20 secured to the usual supporting frame 21 of the aluminum trays. At each side of the trays is a short-circuiting switch consisting of a shaft 12 disposed in line with the series of trays and pivoted preferably to the inside of the 40 container 10. Each shaft has a contact strip 13 mounted thereon by arms 14, the contact strip being of the same extent as or greater 45 than the distance between the top and bottom terminals 11. An arm 15 is connected to each shaft near one end thereof, the arms of both shafts being linked together as at 50 16. The contact strips are preferably of copper, curved or bent to form a convex face and are each electrically connected as at 17 to one conductor of the circuit 5. One of the arms 15 has a grip 55 15^a whereby the arms are moved and when the latter are swung in the direction of the arrow Fig. 4, the contact strips 13 are brought into engagement with the terminals 11 and connect the groups of trays in parallel so that when the switch 6 of the charging 60 circuit is closed the strips 13 and terminals 11 will short-circuit the current and thus as the number of trays in each group is proportionate to the voltage of circuit 5 and the terminals arranged as described, cause

the requisite voltage to pass to each of the 65 trays to build up the film thereon.

The outer ends of the terminals are preferably spring controlled as shown in Fig. 3 so that when the rounded strips 13 engage therewith a positive connection is made.

In recharging an arrester, first one of the horns of the gap is swung clear of the other so as to isolate the arrester from the transmission line and then the short-circuiting switches are closed to connect the groups of 75 trays in parallel. With the rheostat full in the switch is closed and the circuit completed to build up the films. As the films reform, the rheostat is turned so that this resistance is cut out in proportion to the 80 advance in the formation of the films and the increasing resistance set up thereby. To secure the best results it is advisable to repeat this operation three or four times.

What I claim is as follows:

1. The combination with an electrolytic lightning arrester adapted to be applied to a transmission line and including a plurality of aluminum trays having an electrolyte between them and means, for charging said 90 arrester, including an electric circuit separate from that of the transmission line.

2. The combination with an electrolytic lightning arrester adapted to be applied to a transmission line or main circuit, of a circuit 95 additional to the main circuit for charging the arrester.

3. The combination with an electrolytic lightning arrester of cell formation and adapted to be applied to a transmission line 100 or main circuit, of a circuit additional to the main circuit for charging said cells.

4. The combination with an electrolytic lightning arrester adapted to be applied to a transmission line or main circuit and having 105 a plurality of trays with an electrolyte between them, of a circuit additional to the main circuit for charging the arrester.

5. The combination with an electrolytic lightning arrester adapted to be applied to 110 a transmission line and including a plurality of aluminum trays having an electrolyte between them and means, for charging said arrester, including an electric circuit separate from that of the transmission line and a 115 variable resistance in said circuit.

6. The combination with an electrolytic lightning arrester adapted to be applied to a transmission line and including a plurality of aluminum trays having an electrolyte between them and means, for charging said 120 arrester, including an electric circuit separate from that of the transmission line and a switch for controlling said circuit.

7. The combination with an electrolytic lightning arrester adapted to be applied to a transmission line and including a plurality of aluminum trays having an electrolyte be-

- tween them, such trays being tapped off into groups, and means, for charging said arrester, including an electric circuit separate from that of the transmission line and means 5 in said separate circuit for connecting the groups of trays in parallel.
8. In combination with an electrolytic lightning arrester including a plurality of aluminium trays having an electrolyte between them and being tapped off into groups, of an electrical circuit and means included in said circuit for connecting the groups of trays in parallel.
9. In combination with an electrolytic lightning arrester including a plurality of aluminum trays having an electrolyte between them and terminals connected to the trays, of an electrical circuit and short circuiting switches included in said circuit and 20 adapted to be swung into engagement with the terminals upon the trays.
10. The combination with an electrolytic lightning arrester including a plurality of aluminum trays having an electrolyte between them, of means for arranging said trays into groups in parallel and passing an electric current therethrough.
11. In combination with an electrolytic lightning arrester including a plurality of aluminum trays having an electrolyte between them, terminals arranging said trays into groups having an equal number of trays respectively, insulated strips carrying the terminals and pivoted contact strips adjacent to said terminals and adapted to be 30 swung into contact with the latter, of an electrical circuit having said contact strips included therein, a switch in said circuit and a rheostat also in said circuit.
12. The method of charging an electrolytic lightning arrester having a plurality 35 of aluminum trays with an electrolyte between them and being connected in series with an air gap inserted between the arrester and a transmission line, consisting in first increasing the air gap to isolate the arrester from the transmission line and then including the arrester in an electric circuit 45 separate from that of the transmission line.
13. The method of charging an electrolytic lightning arrester having a plurality of aluminum trays with an electrolyte between them and being connected in series with a horn gap inserted between the arrester and a transmission line, consisting in first spacing the horns of the gap to isolate the arrester from the transmission line, arranging the aluminum trays into groups in parallel and then including such groups in an electrical circuit separate from that of the transmission line.
14. The improved method of charging an electrolytic lightning arrester adapted to be applied to a transmission line or main circuit, which consists in charging the arrester 55 by a circuit additional to that of the transmission line.
15. The improved method of charging an electrolytic lightning arrester adapted to be applied to a transmission line or main circuit, which consists in disconnecting the arrester from the main circuit and charging the arrester by a circuit additional to that 60 of the transmission line.
- In testimony whereof, I have signed my name to this specification, in the presence of two subscribing witnesses.
